United States Patent Office

Des. 186,268
Patented Oct. 6, 1959

186,268

WINDOW CLEANER OR SIMILAR ARTICLE

George W. Yearley, Geneva, Ohio, assignor to True
Temper Corporation, Cleveland, Ohio, a corporation of Ohio

Application July 31, 1957, Serial No. 47,168

Term of patent 3½ years

(Cl. D9—2)

Fig. 1 is a rear perspective view of a window cleaner or similar article showing my new design; and

Fig. 2 is a front perspective view of Fig. 1.

The dominant features of my design reside in the portions shown in full lines.

I claim:

The ornamental design for a window cleaner or similar article, as shown and described.
